INVENTOR:

H. M. Albee,

BY Drake & Co., ATTYS.

UNITED STATES PATENT OFFICE.

HONESTUS MORTON ALBEE, OF NEWARK, NEW JERSEY.

WOOD-WORKING MACHINE.

SPECIFICATION forming part of Letters Patent No. 354,997, dated December 28, 1886.

Application filed July 8, 1886. Serial No. 207,405. (No model.)

To all whom it may concern:

Be it known that I, HONESTUS MORTON ALBEE, a citizen of the United States, residing at Newark, in the county of Essex and State of New Jersey, have invented certain new and useful Improvements in Wood-Working Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to facilitate the grooving, channeling, or sinking of panels in the surfaces of various kinds of wood-work—such, for example, as stair-stringers, door and other panels, ceilings or wainscoting, and the like—and especially to facilitate the execution of such work in parallel planes or in angles, or in regular or irregular curves or shapes, and with or without forms or patterns, which work has, as a rule, been heretofore done by hand.

In the accompanying drawings, in which similar letters of reference indicate like parts in each of the several figures, Figure 1 represents in elevation an ordinary jointed frame hung upon a post or to the side of a building so as to be capable of a universal horizontal movement, and having my improvements in part attached thereto. Fig. 2 is an enlarged detached view of the same, showing more fully and clearly said improvements, which are arranged in connection with a piece of wood for operation, and Fig. 3 is a detail view indicating to a limited extent the nature and character of the work designed to be executed by means of my improvements. Fig. 4 is a sectional view illustrating a slight modification, and Fig. 5 is an inverted plan of the cutter preferred.

In said drawings, A, B, and C represent, respectively, the frame and driving-shaft of the machine, which, being constructed and arranged in the ordinary manner, need no further description.

In carrying out my invention a hole is drilled in the lower end of the shaft C, in which is inserted a cutter, D, Fig. 2, of such form as the nature of the service may require. There is

also adjusted upon said shaft C a collar, C', carrying a slotted arm, E, the end of which is supported and works in a circular or curved support or guide plate, F, which is secured firmly to the frame B, as indicated in Figs. 1, 2, and 3. Adjusted in and depending from said slotted arm E is a detachable guide or gage, G, the use of which will be better understood by reference to Fig. 3, and which will be further referred to hereinafter. A vertically-adjustable presser-foot, a, is secured to the collar C', adapted to gage or limit the depth of the cut, groove, or channel, as will be understood by reference to Fig. 2.

In view of the illustrations in the drawings the operation of the machine needs scarcely to be explained further than to state that when cutting a groove parallel with the edge of a board or plank the guide or gage G must be set at the required distance from the cutter, and the presser-foot be set so as to limit the depth of the cut. The movement of the machine in cutting is controlled by the operator by grasping the handle H with one hand, and, if necessary to deviate the course of the cutter from a straight line, by grasping the gage G also with the other, and moving the same to the right or left in a horizontal plane, as will be understood by reference to Fig. 2. When a groove is to be made not parallel with an edge and beyond the scope of the gage G, said gage may be detached or removed, and the course of the cutter be controlled or guided by the operator by means of a pattern or drawing, as will be readily understood.

Under certain circumstances the gage a may be removed, and a collar, I, may then serve as a stop to limit the depth of cut.

The gage G is preferably provided with a roller, G', to engage the edge of the board being worked upon or the pattern, to avoid friction and secure increased freedom of movement.

The cutter employed may be of any suitable construction, the one shown in plan in Fig. 5 being the one preferred.

Having thus described the invention, what I claim as new is—

1. The combination, with the horizontally-movable frame, of a driving-shaft, C, cutter D, collar, as I, mounted upon said shaft, and a vertically-adjustable gage for limiting the depth

of cut, said parts being arranged with relation to one another substantially as set forth.

2. In a wood-working machine, the combination, with the shaft C, of a cutter, D, adapted to be adjusted in a socket in the end of said shaft, and a gage, G, adapted to be moved in a horizontal plane, whereby the track or course of the cutter may be deviated or turned from a straight line, substantially as set forth.

3. The combination, with the horizontally-movable frame or bracket having a driving-shaft, C, of a cutter, D, presser-foot *a*, and guide or gage G, substantially as set forth.

4. The combination, with a horizontally-movable bracket or frame and a driving-shaft, 15 of a cutter, as D, a presser-foot, as, *a*, a guide or gage, as G, and a supporting arm or carrier for

said gage, substantially as and for the purposes set forth.

5. In combination, a horizontally-movable 20 bracket or frame, A B, a driving-shaft carried by said frame B, a cutter adapted to be adjusted in the end of said shaft, a slotted arm, E, working in a guide-plate, F, secured to the frame B, and a gage, G, depending from said 25 slotted arm, substantially as and for the purposes set forth.

In testimony that I claim the foregoing I have hereunto set my hand this 1st day of July, 1886.

HONESTUS MORTON ALBEE.
